UNITED STATES PATENT OFFICE

104,904

DESIGN FOR A BATH BRUSH

Benjamin J. Ryan, Newark, N. J.

Application October 16, 1936, Serial No. 65,319

Term of patent 14 years

To all whom it may concern:

Be it known that I, Benjamin J. Ryan, a citizen of the United States, residing at Newark, in the county of Essex and State of New Jersey, have invented a new, original, and ornamental Design for Bath Brush, of which the following is a specification, reference being had to the accompanying drawing, forming part thereof:

Fig. 1 is a rear perspective view of a bath brush, showing my new design; and

Fig. 2 is a front perspective view thereof.

I claim:

The ornamental design for a bath brush, substantially as shown.

BEN. J. RYAN.
